UNITED STATES PATENT OFFICE

GEORGE GRAFF, OF TOLEDO, OHIO, ASSIGNOR TO THE DURA COMPANY, OF TOLEDO, OHIO, A CORPORATION OF OHIO

DESIGN FOR A CLOCK CASE

Application filed April 28, 1930. Serial No. 35,426. Term of patent 14 years.

To all whom it may concern:

Be it known that I, GEORGE GRAFF, a citizen of the United States of America, residing at Toledo, in the county of Lucas and State of Ohio, have invented a certain new, original, and ornamental Design for a Clock Case, of which the following is a specification, reference being had therein to the accompanying drawings, forming a part thereof, in which—

Figure 1 is a front elevation of a clock case showing my new design; Figure 2 is a side elevation thereof.

I claim:

The ornamental design for a clock case substantially as shown.

GEORGE GRAFF.
